UNITED STATES PATENT OFFICE.

GEORGE WASHINGTON TURNER, OF ARGENTA, ARKANSAS, ASSIGNOR OF ONE-HALF
TO JOHN BOWERS, JR., OF ARGENTA, ARKANSAS.

SPRING-MOTOR FOR FANS.

1,214,848.

Specification of Letters Patent.

Patented Feb. 6, 1917.

Application filed May 20, 1916. Serial No. 98,946.

To all whom it may concern:

Be it known that I, GEORGE W. TURNER, of Argenta, in the county of Pulaski, State of Arkansas, have invented certain new and useful Improvements in Spring-Motors for Fans, of which the following is a full, clear, and exact description, reference being had to the accompanying drawings, forming part of the same.

10 My invention relates to improvements in spring motors and more particularly to spring motors for operating fans.

It has for its object to provide a spring motor for fans which can be operated with 15 a very small amount of energy.

It further has for its object to provide a spring motor for fans which is simple, inexpensive and durable in construction, easy to operate, almost noiseless, convenient to 20 use and which furnishes a maximum amount of power with a minimum output or amount of energy.

It further has for its object to provide a motor which can be operated without the 25 use of electricity, gas, gasolene, alcohol and the like and which can be conveniently transported to any place where it is desired to use the same.

My invention consists in the several features and in the construction, combination and arrangement of features as more fully 30 hereinafter described and claimed.

Referring to the drawings:—

Figure 1 is a front elevation of my invention.

Fig. 2 is a side elevation with the casing shown in section to clearly show the operative parts mounted therein.

Fig. 3 is a detail front view of one of the 40 depending lugs of the casing.

Fig. 4 is a detail view of the brake lever and the securing means therefor.

In the drawings in which like reference characters denote like parts throughout the 45 several views, 1 represents the casing inclosing the operative mechanism of the fan, which is provided with depending lugs 2 and 3 each provided with a hole 4 therethrough and the lug 2 being provided with a hole 5 just above the hole 4.

The casing is provided at the top with an

upwardly extending hood or cap 6 in which the shaft carrying the fan is mounted as hereinafter described.

7 is the base on which the casing 1 is pivotally mounted, by means of a pin 7^a which in turn is mounted in the holes 4, to adapt the casing to be adjusted forwardly and rearwardly, and provided with an upwardly extending lug 8 having a series of preferably 60 shallow recesses 9, 10 and 11 formed in the face of the lug, and 12 is a spring controlled pin which is mounted in the hole 5 of the lug 2 adapted to engage the shallow recesses 9, 10 and 11 of the lug 8. 65

When it is desired to fix the casing in a vertical position the pin 12 is adapted to engage the recess 9; when it is desired to fix the casing in a forward position the pin is adapted to engage the shallow recess 10 and 70 when it is desired to fix the casing in a rearward position the pin is adapted to engage the shallow recess 11.

Shafts 12, 13, 14, 15, 16, 17, 18 are mounted in the casing and 19 and 20 are gears of 75 a train of intermeshing gears mounted on said shafts.

The shaft 18 is provided with a gear 25 which engages the gear 21 and outside the casing a handle 26 is provided designed to 80 be fitted on the outer end of the shaft 18 and be used to wind the clock spring 22.

The shaft 17 is provided with a gear 21 having the well known clock operating spring 22 therein and provided with a 85 ratchet 23 on its face and a pawl 24 is pivoted to the casing 1 and engages the ratchet.

The shaft 12 is provided with a bevel gear 27 which engages a bevel gear 28 on a vertical shaft 29, mounted on the top of the casing, 90 and a bevel gear 30 on the upper end of the shaft 29 engages a bevel gear 31 on the shaft 32 which carries the fan 33.

In order to slow down the speed of the fan, or stop it altogether a friction brake 34 95 is provided which comprises a friction wheel or disk 35 mounted on the shaft 12 and a lever 36 pivoted to the casing 1 is adapted to be moved laterally and abut and engage the side of the friction wheel 35. 100

The side of the wheel 35 or the side of the lever 36 may be provided with a covering

of leather, rubber or other suitable material to prevent wear of the contacting parts and assist in making a close contact.

In order to retain or lock the lever 36 in its proper relative position to the friction wheel 35, ratchet teeth 37 are provided on the lower edges of the opening 38 in the casing which are adapted to be engaged by the tooth 39 depending from the lever 36.

10 The operation is so obvious that I have not thought it necessary to describe it.

I do not wish to be understood as limiting myself to the specific details of construction and arrangement as herein described and illustrated, as it is manifest that variations and modifications may be made in the features of construction and arrangement, in the adaptation of the device to various conditions of use, without departing from the 20 spirit and scope of my invention and improvements. I therefore reserve the right to all such variations and modifications as

properly fall within the scope of my invention and the terms of the following claim.

What I claim is:—

25 In a spring motor for fans, a base, a closed casing the lower portion of which is directly pivoted to said base, means for securing said closed casing in angularly adjusted positions about said pivot, a train of gearing, a gear having a spring therein for actuating said train of gearing and means for winding the spring in said gear all located in said closed casing, a reduced closed cap at the upper portion of said closed casing, a fan shaft 35 and gears mounted within said reduced closed cap operatively connected with the train of gears in said closed casing, a fan on said fan shaft located outside of the closed cap and casing and beyond the front faces 40 thereof and a brake lever mounted in said closed casing.

GEORGE WASHINGTON TURNER.
